Inventor:

Frederick Hawkins

United States Patent Office.

FREDERICK HAWKINS, OF CHICAGO, ILLINOIS.

Letters Patent No. 78,284, dated May 26, 1868.

IMPROVED CONCRETE-BRICK MACHINE.

The Schedule referred to in these Letters Patent and making part of the same.

TO ALL WHOM IT MAY CONCERN:

Be it known that I, FREDERICK HAWKINS, of Chicago, in the county of Cook, in the State of Illinois, have invented a useful Improvement in Concrete-Brick Presses; and I do hereby declare that the following is a full and exact description thereof, reference being had to the accompanying drawings, and to the letters of reference marked thereon, making a part of this specification, in which—

Figure 1 is a sectional elevation of my invention.

Figure 2, a top view of the pressing-box, with the sliding lid removed.

Figure 3, a top view of the devices for pressing the bricks.

Figure 4, an elevation of the clutch for coupling the pressing-devices.

This invention relates to that kind of presses used in the manufacture of artificial building-stone and concrete brick, and for this reason it is arranged to press only one brick at a time, and by hand-power.

Its nature consists more especially in a novel arrangement for guiding and operating the lid, whereby it may be opened and closed more readily, and at the same time not be affected in its operation, when the edges become considerably worn, by means of sand and concrete.

To enable others to make and use my invention, I have marked corresponding parts with similar letters, and will now give a detailed description.

A represents one side of the frame, which supports two uprights, B, made of iron or other suitable material, and to form the ends of the pressing-box L L similarly to the common presses now in use for a similar purpose.

S S, figs. 1 and 2, represent flanges projecting outward from the vertical sides of the mould L L, and arranged to support a sliding lid, M, which is fitted to run in grooves made in flanges C C, at the ends of the press.

This arrangement, thus far, is similar to T. H. Rogers's press, patented April 10, 1866, but the arrangement for guiding and operating the lid M is very different, and as follows:

A slot, v, is made in one of the flanges, S, of such a size as will correspond with the thickness of the rack T, fig. 1, which is made to run in said slot, and thus guide the lid when being opened and closed. This construction in presses of this kind I consider new and of importance, otherwise the lid, as soon as its edges become worn, would not operate easily, as the corners would bind in the grooves, and the rack would soon wear out by lateral motion.

The rack T is rigidly attached to the under side of the lid M, and is operated by means of a pinion, W, having a shaft, X, with suitable bearings attached to standards B, a common crank, a, being used to turn said shaft in the usual manner. All of the upper part of the press, including the standards B, should be made of iron, and the lid M, especially, fitted to work easily, and also fit the top of the mould L L closely. The levers Q, R, H and I, should be made of iron, and of such lengths as will raise the follower N high enough to press a brick or building-block compactly together.

In the drawings the levers H I are represented as attached to a drum, E, by means of a chain, F, a wheel, Z, attached to said drum being used to raise and lower the levers, and thus press the brick and lower the follower N.

The device for raising the brick out of the mould consists of a shaft, having bearings in the uprights B, and supporting a pinion, P, fig. 1, which operates a rack rigidly attached to the shank of the follower V.

In the foregoing description, some parts of the press are simply enumerated, but as they are well-known devices, no trouble will be experienced in constructing a press according to the drawings.

Having thus described my invention, what I claim, and desire to secure by Letters Patent of the United States, is—

The mould L L', provided with slotted flange S and lid M, with its rack T and pinion W, the follower N, with its rack Q' and pinion P, levers Q, R, I, and H, chain F, drum E, and wheel Z, all arranged and operated substantially as and for the purposes herein set forth.

FREDERICK HAWKINS.
